CASING FOR STEAM OR GAS TURBINES

Oscar Anton Wiberg, Finspong, Sweden

Application March 16, 1932, Serial No. 599,294
and in Germany March 13, 1931

11 Claims. (Cl. 253—16.5)

In steam or gas turbines the casing which encloses the blading is subjected to different temperatures at different points. This will give rise to high stresses in the material of the casing, whereby fatiguing thereof and breakage may result. Especially in case of radial flow turbines which operate on the counter pressure principle, and in which an outer casing and an inner casing are provided, such stresses most frequently appear in the inner casing. The inner casing of such a turbine usually comprises two halves bolted together. In case of a turbine of this kind, having blades and discs rotating in opposite directions, each half of the inner casing comprises one annular lateral steam or gas chest at least, and is formed outside this chest or chests with a cup shaped wall, in such a way that the cup shaped walls of both halves, when brought together to form the casing, will provide an outer chamber to receive the exhaust gas or steam discharged from the turbine blading. In order to take care of the stresses in the material due to the different temperatures, said cup shaped walls are made yieldable. Nevertheless, the material will be subject to fatigue due to the continuously varying temperature, and breakage will, consequently, follow sooner or later. Said variations of temperature are due to the fact that the driving medium, such as gas or steam, supplied to the annular lateral chest is, normally, of a considerably higher temperature than that of the exhaust medium discharged from the blading.

The object of the invention is to overcome the above said drawback without necessitating the manufacture of the casing, subjected to the different temperatures, from an expensive material of such a high quantity as to permit the action of such stresses.

To this end said turbine casing, according to the present invention, comprises a plurality of members steam- or gas-tightly connected together by expansion elements. This will permit the use of a cheap material of moderate strength as material for the casing.

In the accompanying drawings the invention is illustrated by way of example.

Fig. 1 is an axial section, taken on line I—I of Figs. 2 or 5, of the upper portion of a radial flow turbine having blades and discs rotating in opposite directions and provided with an inner casing according to this invention. Fig. 2 is a cross section on a reduced scale taken on line II—II of Fig. 1, showing the inner casing of the turbine. Figs. 3 and 4 are cross sections on a larger scale of various forms of expansion elements used to

connect the members of the inner turbine casing to each other. Fig. 5 is a cross section of an inner turbine casing of a modified construction. Fig. 6 is an axial section of a turbine similar to Fig. 1, but having double expansion rings. 60

With reference to Fig. 1, the numeral 1 indicates the outer casing of a turbine having also an inner casing comprising two lateral members 2, 2 and one intermediate member 3. 4 and 5 indicate two oppositely rotating shafts which each 65 carry a turbine disc 6 and 7, respectively, with the associated blading 8. Inserted between the shafts and the members 2, 2 of the inner casing are shaft packings 9, 9. Each lateral member 2 of the inner turbine casing contains an annular 70 chamber 10 and 11, respectively, and the intermediate member 3 contains a chamber 12 surrounding the blading 8. The members 2, 2 containing the lateral chambers 10 and 11 are carried by the outer casing 1 through the intermedium of rings 13, 14 secured to said outer casing, and expansion elements. In addition, the members or walls 2 are rigidly connected together by means of bolts 15 extending through annular 75 outer flanges of the members 2. The member 3 of the inner casing is carried by the members 2, 2 through the aid of expansion elements 16, 16 which comprise resilient rings connecting said outer flanges of the members 2, 2 to the inner periphery of the member 3. Said member 3 is provided with axially extending stays 17 through which the bolts 15 extend. The borings of said stays 17 to receive the bolts 15 surround the bolts with a given play so as to allow the members 2, 2 to expand and contract independently of the member 3. 80

As shown in Fig. 2 the member 3 contains two chambers 12, 12 each surrounding half the periphery of the blading, and each provided with a separate outlet 18. The two outlets 18 are 95 situated at diametrically opposite points. The cross section of the stays 17 is of streamline form in order to afford a low resistance to the exhaust steam or gas.

Fig. 5 illustrates another embodiment of an inner turbine casing constructed according to this invention. The member 3 contains two chambers 12, but only one outlet 19 common to both chambers. 100

Fig. 3 shows an expansion ring 16 cut at right angles at both ends, whereas Fig. 4 shows an expansion ring formed with rounded ends. In both of these figures packing material 20 is inserted between the ends of the rings and the bottom of the grooves receiving the ends of the rings. It is 110

to be noted, however, that the rings may also engage the grooves without interposed packing material. The rings 16 should be of a sufficient axial length to allow the relative displacements of the members of the casing with respect to one another. It is to be noted that the larger the axial length of the rings, the higher is the elasticity of the rings, and the lower is the bending stress.

In the operation of a steam turbine having an inner casing constructed as described, the members 2, 2 of said casing, the chambers 10 and 11 of which contain steam of a higher temperature than that of the steam contained in the chamber 12 of the member 3, have a tendency of expanding 10 to a higher degree than the member 3. The members 2, 2 when thus expanding, will carry the bolts 15 with them and, when thus acted on, the bolts may move freely in the borings of the stays 17. The expansion rings 16 due to the expansion 15 of the members 2, 2 are now bent so as to assume a cup shape. As a result, said rings will transmit a pressure to the member 3 to a certain degree. If, however, the rings 16 are manufactured from a good material of high strength and 20 high elasticity, the pressure transmitted through said rings will be very low, and it is, therefore, sufficient to use as material for the various members of the turbine casing a cheap material of very low elasticity, because in such case said last- 25 mentioned material need only satisfy moderate conditions as to strength and elasticity.

In case a breakage occurs it may be assumed that, in the most cases, said breakage has occurred in the expansion rings. In such case one 30 ring only or both rings need be replaced while, hitherto, it was necessary to replace the entire casing.

Instead of the expansion rings 16 other expansion elements may, of course, be used without departing from the principle of the invention. Instead of single expansion rings between the intermediate and lateral members 3 and 2, 2 of the inner casing, double rings may be used, for instance, as shown in Fig. 6, where in addition to the ring 16, situated inside the set of connecting bolts 15 a similar ring is provided outside of said set of bolts, as shown at 21.

The bolts 15 may be hollow in order that they may rapidly be heated to the temperature of the surroundings. The stays 17 are preferably uniformly distributed around the entire blading.

What I claim is:—

1. A casing for a radial flow elastic fluid turbine and its blading comprising, a plurality of 55 separate members axially spaced apart, each of said members having a fluid chamber, an intermediate member between said first-mentioned members, axially extending elements connecting two of the first-mentioned members together for expansive movement independent of the intermediate member, and axially extending expansion elements yieldingly connecting adjacent members to each other.

2. The combination with a radial flow elastic fluid turbine and its blading, of an outer casing and an inner casing comprising three separate members, viz. two lateral members positioned on opposite sides of the turbine blading and one intermediate member situated axially 60 between said lateral members, each of said lateral members containing at least one annular chamber to receive the driving fluid and distribute it to the blading, the intermediate member containing at least one chamber to receive the 65 exhaust fluid discharged from the blading,

expansion elements to connect the lateral members to the outer casing, expansion elements to connect said intermediate member to said lateral members in such a way that said lateral members may carry the intermediate member by the aid of said expansion elements, and means acting independently of said intermediate member to press said lateral members against said expansion elements.

3. A casing for a radial flow elastic fluid turbine and its blading, comprising two separate lateral members positioned on opposite sides of the turbine blading and one intermediate separate member, axial bolts to connect said lateral members to each other for expansive movement independent of said intermediate member, and expansion elements to connect said intermediate member to said lateral members and to form steam-tight joints therebetween, said lateral members each having at least one annular chamber in communication with the center of the blading, and said intermediate member having separate chambers in communication with individual parts of the outer periphery of the blading.

4. A casing for radial flow elastic fluid turbines, comprising two separate lateral members on opposite sides of the turbine blading to receive driving fluid and distribute it to the blading, one separate intermediate member to receive the exhaust fluid discharged from the blading, axial stays in said intermediate member, bolts extending with play through holes in said stays to connect the lateral members to each other for expansive movement independent of said intermediate member, and expansion elements to connect said intermediate member to said lateral members.

5. A casing for a radial flow elastic fluid turbine and its blading, comprising three separate 115 members displaced axially with relation to each other, these members consisting of two lateral members situated on opposite sides of the turbine blading and one peripheral member situated axially between said lateral members so as to surround the blading, axial stays of streamline section in said peripheral member, axial bolts extending with play through holes in said stays to connect said lateral members to each other for expansive movement independent of said peripheral member, and axial expansion rings to yieldingly connect said peripheral member to said lateral members and to form steam-tight joints therebetween.

6. A casing for radial flow elastic fluid turbines, comprising a peripheral member and lateral members displaced axially with relation to each other, each of said members containing independent fluid chambers, axial stays of streamline cross section in said peripheral member, 135 axial bolts to connect said lateral members for expansive movement independent of said peripheral member, and axial elastic rings to connect said peripheral member to said lateral members in such a way that the lateral members 140 may carry the peripheral member by the aid of said elements.

7. A casing for radial flow elastic fluid turbines, comprising a peripheral member to receive fluid that has expanded to a certain degree in the 145 turbine and two opposite lateral members, axial bolts to rigidly connect said lateral members to each other for expansive movement independent of said peripheral member, and expansion elements by means of which said lateral mem- 150

- bers may support said peripheral member, and which elements form steam-tight joints between the members.
8. A casing for radial flow elastic fluid turbines, comprising a peripheral member to receive driving fluid that has expanded to a certain degree in the turbine and two opposite lateral members to receive fresh driving fluid and distribute it to the turbine, axial hollow stays of streamline cross section in said peripheral member, axial bolts extending through said hollow stays to connect said lateral members to each other for expansive movement independent of said peripheral member, and expansion elements by means of which said peripheral member is supported by said lateral members, and which elements form steam-tight joints between said members. 80
10. A casing for radial flow elastic fluid turbines, comprising a peripheral member to receive driving fluid that has expanded to some degree in the turbine, and two opposite lateral members to receive fresh fluid and distribute it to the turbine, axial hollow stays of streamline cross section said peripheral member, axial bolts extending with play through said hollow stays to connect said lateral members to each other for expansive movement independent of said peripheral member, and axial elastic rings, by which 85 said peripheral member is connected to said lateral members so as to be supported thereby. 90
11. In an elastic fluid turbine, the combination with a rotary blading for radial flow and an outer stationary casing of an inner stationary casing, comprising two lateral members on opposite sides of the blading, and each containing one annular chamber at least to receive the driving fluid and distribute it to the blading, and one intermediate peripheral member containing separate chambers each surrounding an individual portion of the circumference of the blading, and communicating therewith so as to receive the exhaust 95 fluid discharged therefrom, axial hollow stays of streamline cross section in said peripheral member, axial bolts to rigidly connect said lateral members to each other for expansive movement independent of said peripheral member, said 100 bolts extending with play through said hollow stays, axial elastic rings by which said peripheral member is connected to said lateral members so as to be supported thereby, and separate outlets in said peripheral member leading from the individual chambers thereof. 105
12. In an elastic fluid turbine, the combination with a rotary blading for radial flow and an outer stationary casing, of an inner stationary casing, comprising two lateral members on opposite sides of the blading, and each containing at least one annular chamber to receive fresh driv- 110
13. In an elastic fluid turbine, the combination with a rotary blading for radial flow and an outer stationary casing, of an inner stationary casing, comprising two lateral members on opposite sides of the blading, and each containing at least one annular chamber to receive fresh driv- 115
14. In an elastic fluid turbine, the combination with a rotary blading for radial flow and an outer stationary casing, of an inner stationary casing, comprising two lateral members on opposite sides of the blading, and each containing at least one annular chamber to receive fresh driv- 120
15. In an elastic fluid turbine, the combination with a rotary blading for radial flow and an outer stationary casing, of an inner stationary casing, comprising two lateral members on opposite sides of the blading, and each containing at least one annular chamber to receive fresh driv- 125
16. In an elastic fluid turbine, the combination with a rotary blading for radial flow and an outer stationary casing, of an inner stationary casing, comprising two lateral members on opposite sides of the blading, and each containing at least one annular chamber to receive fresh driv- 130
17. In an elastic fluid turbine, the combination with a rotary blading for radial flow and an outer stationary casing, of an inner stationary casing, comprising two lateral members on opposite sides of the blading, and each containing at least one annular chamber to receive fresh driv- 135
18. In an elastic fluid turbine, the combination with a rotary blading for radial flow and an outer stationary casing, of an inner stationary casing, comprising two lateral members on opposite sides of the blading, and each containing at least one annular chamber to receive fresh driv- 140
19. In an elastic fluid turbine, the combination with a rotary blading for radial flow and an outer stationary casing, of an inner stationary casing, comprising two lateral members on opposite sides of the blading, and each containing at least one annular chamber to receive fresh driv- 145
20. In an elastic fluid turbine, the combination with a rotary blading for radial flow and an outer stationary casing, of an inner stationary casing, comprising two lateral members on opposite sides of the blading, and each containing at least one annular chamber to receive fresh driv- 150
